(57) **CLAIM**

The ornamental design for a partially transparent lid for a cooking device, as shown and described.

DESCRIPTION

FIG. 1 is a right-side perspective view of a partially transparent lid for a cooking device showing my new design; FIG. 2 is a front elevation view thereof; FIG. 3 is a back elevation view thereof; FIG. 4 is a right elevation view thereof; FIG. 5 is a left elevation view thereof; FIG. 6 is a top plan view thereof; and, FIG. 7 is a bottom plan view thereof.

The broken lines shown in the drawings are shown for illustrating unclaimed portions of the article and presently, form no part of the claimed design.
